ENGINE FOUNDATION FOR VEHICLES

Brunolf C. Baade, Dessau, Anhalt, Germany, assignor, by mesne assignments, to Wingfoot Corporation, Akron, Ohio, a corporation of Delaware

Original application May 5, 1934, Serial No. 724,112. Divided and this application February 8, 1939, Serial No. 255,270

3 Claims. (Cl. 105—172)

This invention relates to an engine or motor foundation for vehicles and is a division of my patent application, Serial No. 724,112 filed May 5, 1934.

The object of this invention is to combine the engine foundation of a motor vehicle with the fuel, oil and water tanks into one unit in order to save valuable space and to make this space available for other purposes.

Another object of this invention is to construct the engine foundation in such a way that it also will serve as a portion of the floor structure and as outer cover of the vehicle body thereby distributing the weight of the engine and service liquids uniformly over the frame structure.

A further object of this invention is to locate the various service liquids required for operating the power engine as close as possible to the engine to save on length of the necessary piping and to keep the center of gravity of the vehicle as low as possible, in order to obtain a good riding quality.

This invention is described in the following specification and the attached drawing illustrating its adaptation to a car body.

Fig. 1 is a plan view of the invention.

Fig. 2 is a cross-sectional view along the line 2—2 in Fig. 1, showing the engine foundation extending the full height of the floor structure.

Fig. 3 also is a cross-sectional view of this invention in a modification showing a separate bottom for the car structure.

Figs. 1 to 3 show an improved construction of an engine foundation of a railway car, preferably made of welded steel plates. This engine foundation not only supports the main power unit of the car, but also serves as a fuel, oil and water tank, and besides as a floor structure which connects the main longitudinal supporting girders of the car body. Such a combination makes the bottom of the car body tremendously rigid and solves the storage of the service liquids in the most ideal way, since it will bring the center of gravity of the car very low. A great advantage of this construction is the possibility of integrally connecting the power unit foundation with the structural portion of the car body. Another advantage is that the pipe lines (not shown) leading from the storage tanks to the power unit will be very short and therefore simple and direct.

The foundation member 11 of the power unit 12 is divided by longitudinal partitions 13 and transverse partitions 14 and 15 into a number of compartments reserved for fuel, oil and water. The partition walls also serve as stiffeners. The

partitions 14 are provided with openings 16 and 17 to unite two or more compartments into a single one, depending on requirements. The partitions 15 are unperforated. The top 18 of the foundation plate (Fig. 2) rests on the longitudinal supporting girders 19 of the car body and also carries the floor 20. The bottom 21 of the foundation member forms the bottom of the car body. An extension bracket 22 welded to the bottom 10 of the foundation member is secured by bolts 23 to a flange of the longitudinal supporting girders of the car body and the top of the foundation member is fastened to the top of the supporting girders by bolts 24 and 25. Hand-holes 30 and 31 15 are provided in the foundation member to make the bolts accessible.

The power unit may be fastened to the foundation member either directly or a resilient member 32 may be employed between the foundation member and power unit to reduce the vibration transmitted to the car body.

Fig. 3 shows a modification of the arrangement shown in Fig. 2. The foundation member in this case is made of lower height. Instead of securing the foundation member 35 rigidly to the car body, a resilient mounting 36 is employed, whereas the power unit 12 is fastened rigidly by bolts 37 to the foundation member. In order to give the car body sufficient rigidity, transverse members 38 connect the longitudinal supporting girders 19. Because of the large supporting width and mass of the power unit foundation member, its resonance is far below that of the engine and therefore will not transmit undue vibrations into the car body.

It is believed that the foregoing invention is a great advancement in engine foundations for vehicles. However, it should be understood that the construction shown in the drawing shall only serve as an example of which many departures may be made within the spirit and scope of this invention as defined by the appended claims.

I claim:

1. In a railway car, a car body, including two longitudinal supporting girders forming the lower edges of the car body, transverse members connecting said supporting girders, an engine foundation connecting member above and resiliently supported on said transverse members and forming a container to be used for storing a service liquid.

2. In a railway car, a car body, including two longitudinal supporting girders forming the lower edges of the car body, transverse members connecting said supporting girders, an engine foun-

dation connecting member above and resiliently supported on said transverse members and forming a container to be used for storing a service liquid, the top of the foundation plate being arranged to serve also as a support for a portion of the car body floor.

3. In a railway vehicle the combination with

longitudinally extending supporting girders forming the outer lower edges of the car body, of a storage tank resiliently supported on and extending between said girders, and a motor mounted on and carried by said tank.

BRUNOLF C. BAADE.
